UNITED STATES PATENT OFFICE.

EDWARD L. GOODIN, OF COPELAND, ARKANSAS, ASSIGNOR OF ONE-THIRD TO GEORGE B. M. WILL, OF CRABTREE, ARKANSAS.

LAUNCHING DEVICE FOR AEROPLANES.

Application filed January 20, 1923. Serial No. 613,926.

To all whom it may concern:

Be it known that I, EDWARD L. GOODIN, a citizen of the United States, residing at Copeland, in the county of Van Buren and 5 State of Arkansas, have invented certain new and useful Improvements in Launching Devices for Aeroplanes, of which the following is a specification, reference being had to the accompanying drawings.

10 This invention relates to improvements in launching devices for aeroplanes, and more particularly to a device carried by the plane by means of which it may be given a forward impulse for launching the same 15 into the air.

An important object of the invention is to provide a device of this character which is readily controllable by the operator of the vehicle and which requires minimum 20 attention on the part of the operator in order that he may give the proper attention to the ordinary controls of the plane.

A further object of the invention is to provide a device of this character which is extremely simple in its construction and 25 operation and which may be readily applied to planes as now constructed.

A still further object of the invention is to provide a spring drum structure having 30 means for preventing rotation of the drum in one direction and a brake for preventing operation of the drum under influence of the spring thereof, the brake and first 35 named means being so constructed that upon release of the brake the first named means is held out of engagement with the drum by said means.

Other objects and advantages will become apparent throughout the course of the following description.

In the accompanying drawings wherein for the purpose of illustration is shown a preferred embodiment of my invention and wherein like reference characters designate 45 like parts throughout:

Figure 1 is a plan view of an aeroplane partially diagrammatic showing launching apparatus in accordance with my invention applied thereto;

50 Figure 2 is a plan view of the launching apparatus;

Figure 3 is a sectional view taken therethrough; and

55 Figure 4 is a detail view showing the speed control for the drum.

Referring now more particularly to the drawings, the numeral 10 indicates a frame in which is rigidly mounted a shaft 11. Upon the shaft within the frame a drum 12 is rotatably mounted, said drum having 60 therein a plurality of springs 13 of the clock work type, one end of the springs being connected to the shaft and the opposite end thereof to the drum. The drum is provided with a flange 14 having formed 65 in one side face thereof beveled gear teeth 15 for coaction with a pinion 16 mounted upon a shaft directed through one side of the frame and having upon its outer end means, as at 17, whereby it may be rotated. 70

The outer edge of the flange 14 is provided with ratchet teeth 18 having the shoulders thereof facing in the direction of rotation of the drum when driven by the springs 13. The wall of the frame 10 is 75 provided at one side thereof with an extension 19 in substantial alignment with the flange 15 and this extension has pivoted thereto a lever 20 formed at one end with a dog 21 for engaging the ratchet teeth 18 80 and at the opposite end with a hand portion 22 by means of which it may be shifted about its pivot to withdraw the same from the ratchet teeth to permit rotation of the drum. A spring 23 secured to the extension 19 and abutting the pawl end of the lever 20 normally maintains this lever with the pawl thereof in engagement with the ratchet teeth 18. The under surface of the handle end of the lever 20 has formed 90 thereon a shoulder 24 for a purpose presently to appear.

The flange 14 is provided upon one side thereof with a flange 25 in the form of a shoulder with which coacts a brake band 26, one end of which is secured to the frame 10 and which after passing about the flange 25 has its opposite end secured to one end of a bell crank lever 27, the pivot of which is arranged approximately beneath the shoulder 24 of the lever 20. The other arm of the bell crank lever 27 has formed thereon a foot treadle 28 by means of which it may be depressed to tighten the brake band. When the brake band is fully 100 tightened and has sufficient tension to check rotation of the drum, the end of the bell crank lever engaged by the brake band 26 is aligned with the face 24a of the shoulder 24 of the lever 20 to be received thereby, 110

whereby return movement of the bell crank lever 27 to slacken the brake band is prevented. This shoulder is of sufficient depth to permit engagement of the ratchet teeth 5 by the pawl 21 and accordingly the drum is held against rotation both by the pawl and brake.

In use, the frame 10 and spring drum is arranged within the fuselage of the aero 10 plane and has wound thereabout a cable 29, the cable being wound upon the drum in a direction to be released thereby when the drum is rotated to tension the springs 13 and accordingly to be wound upon the drum 15 when the drum is rotated by the springs. The end of this cable 29 has secured thereto an eye 30 adapted to be placed over a stake 31 placed in the ground and inclining away from the aeroplane to be launched, the 20 cable of course having the ring thereof engaged with the stake when fully extended or when the drum springs are fully tensioned. In launching the plane, the brake band 26 is tensioned by placing the foot 25 upon the treadle 28 and the handle end 22 of the lever 20 elevated to withdraw the pawl. The brake 26 is then released, the band engaged end thereof moving forwardly, and the action of the springs causes the 30 winding of the cable upon the drum and a consequent forward movement of the aeroplane. The end of the bell crank lever having attached thereto the brake band is of such a length that when moved forwardly 35 to release the brake band, it engages the shoulder 24 and acts as a prop or stay, maintaining the pawl end of the lever 20 out of engagement with the ratchet teeth 18, thereby preventing engagement of the pawl posi- 40 tively. When it is desired to tension the springs, the bell crank lever is engaged with the hand as is the pawl 22 and the pawl is elevated to permit passage of the arm 27 of the lever by the shoulder 24 and until 45 this arm engages the face 24^b of the shoulder 24. The pawl is then released and is moved by its spring 23 into engagement with the ratchet teeth 18. The brake is likewise held in the full released position so that it ap- 50 plies no friction whatever to the drum tend- ing to resist the winding motion.

If desired, means may be provided for controlling the speed of rotation of the drum 12 other than the brake 26. In the 55 present instance this means is shown as comprising a spring governor 32 driven from the gear teeth 15 of the flange 14 and having its longitudinally shifted part 33 connected, as at 34, with an extension 35 formed upon 60 the hub portion of the bell crank lever 27, the connection being such that when the longitudinal shiftable member is shifted by increased speed, the bell crank lever is rotated upon its pivot in a direction to tension 65 the brake band 26.

It will, of course, be obvious that the control means recited is but one of many forms which may be employed and that otherwise many changes are possible in the construction of my invention without materially departing from the spirit thereof. I accordingly do not limit myself to such specific structure as hereinbefore set forth, except as hereinafter claimed.

I claim:—

1. In a launching device for aeroplanes, a spring drum carried by the aeroplane and having wound thereon a cable unwound by tensioning of the springs of the drum, a ratchet and pawl means for preventing rotation of the drum in a direction winding the cable thereon, a brake for the drum, an operating mechanism for the brake, an engagement between the brake operating means and said pawl locking the brake operating means against movement when the brake is tensioned.

2. In a launching device for aeroplanes, a spring drum carried by the aeroplane and having wound thereon a cable unwound by tensioning of the springs of the drum, a ratchet and pawl means for preventing rotation of the drum in a direction winding the cable thereon, a brake for the drum, an operating mechanism for the brake, an engagement between the brake operating means and said pawl locking the brake operating means against movement when the brake is tensioned and preventing engagement of the pawl when the brake is released.

3. In a launching device for aeroplanes, a spring drum carried by the aeroplane and having wound thereon a cable unwound by tensioning of the springs of the drum, a ratchet and pawl means for preventing rotation of the drum in a direction winding the cable thereon, a brake for the drum, an operating mechanism for the brake, an engagement between the brake operating means and said pawl locking the brake operating means against movement when the brake is tensioned and preventing engagement of the pawl when the brake is released, and means other than said brake for controlling the speed of rotation of the drum.

4. In a launching device for aeroplanes, a spring drum carried by the aeroplane and having wound thereon a cable unwound by tensioning of the springs of the drum, a ratchet and pawl means for preventing rotation of the drum in a direction winding the cable thereon, a brake for the drum, an operating mechanism for the brake, an engagement between the brake operating means and said pawl locking the brake operating means against movement when the brake is tensioned or when the brake is fully released.

5. In a launching device for aeroplanes,

a spring drum carried by the aeroplane and having wound thereon a cable unwound by tensioning of the springs of the drum, a ratchet and pawl means for preventing rotation of the drum in a direction winding the cable thereon, a brake for the drum, an operating mechanism for the brake, an engagement between the brake operating means and said pawl locking the brake op-

erating means against movement when the 10
brake is tensioned and preventing engage-
ment of the pawl when the brake is released,
said brake being shiftable to released posi-
tion permitting engagement of the pawl.

In testimony whereof I hereunto affix my
signature.

EDWARD L. GOODIN.
